UNITED STATES PATENT OFFICE.

DAVID S. SHEHADY, OF SAN FRANCISCO, CALIFORNIA.

OIL-SAVER.

1,302,231.

Specification of Letters Patent. Patented Apr. 29, 1919.

Application filed June 13, 1918. Serial No. 239,907.

To all whom it may concern:

Be it known that I, DAVID S. SHEHADY, a citizen of the United States, residing at the city and county of San Francisco and 5 State of California, have invented new and useful Improvements in Oil-Savers, of which the following is a specification.

This invention relates to an oil saver for internal combustion engines and the like, 10 and particularly to means for returning superfluous lubricating oil from the cylinders to the crank case of the engine.

One of the objects of the present invention is to provide a piston in which is formed 15 a plurality of oil collecting grooves, said grooves adapted to scrape off or remove any superfluous oil delivered to the cylinder by splash from the crank case and in conjunction therewith to provide means for removing 20 the oil collected in the piston grooves and returning the same to the crank case. Another object of the invention is to utilize 25 the suction of the manifold for this purpose and also to employ a separating chamber for separating the oil from the air before it is returned to the crank case. Further objects will hereinafter appear.

The invention consists of the parts and the combination, construction and arrangement 30 of parts as hereinafter more fully described and claimed, having reference to the accompanying drawings, in which—

Figure 1 is a side elevation of a standard form of internal combustion engine, showing 35 the application of the invention.

Fig. 2 is a vertical central section of one of the engine cylinders showing the manner of collecting and removing the oil therefrom.

40 Fig. 3 is a central vertical section of the oil separator and collector.

Referring to the drawings in detail, A indicates the cylinders of an internal combustion engine, 2 the intake manifold, 3 the 45 crank case and 4 the pistons, one of which is reciprocally mounted in each cylinder. Formed intermediate of the upper rings 5 on each piston and the lower ring 6 is a plurality of V-shaped oil collecting grooves 7. 50 These grooves tend to scrape off any superfluous oil which may have been delivered to the cylinders and may therefore serve as annular pockets in which the oil may be collected.

55 Formed in the lower portion of each cylinder is an opening 8 which, in this instance,

is connected with a suction manifold 9. This manifold connects with each cylinder, as shown at 8 in Fig. 1, and the opposite end of the manifold is connected through a pipe 60 10 with an oil separating and collecting tank, shown at 11. This tank may be constructed in any suitable manner, being provided at the upper end with a head 12 and at the lower end with a drain pipe 13 in one 65 end of which is mounted a check valve 14, while the opposite end connects with the crank case, as at 15. Also connected with the tank 11 is a suction pipe 16 which is connected with the inlet manifold 2, as shown 70 at 17.

In actual operation, with the engine running, it can be seen that each piston during its reciprocal movement will pass over the openings 8. The collecting grooves 7, during 75 their passage by said openings, will empty themselves of oil due to the suction in the manifold 9. This oil enters through pipe 10 and is permitted to settle in the tank 11, the check valve 14 being closed as long as the 80 engine is running, due to the constant vacuum or suction maintained within the tank through the pipe connection 16 and the intake manifold 2. This check valve, however, opens the moment the engine stops as 85 the vacuum or suction will immediately be relieved, thus permitting any oil collected to drain back or return to the crank case. In certain instances it happens that the lower end of each piston passes above the suction 90 openings 8. This would permit air to enter the manifold 9 and tank 11 and would therefore be obviously detrimental as too much auxiliary air would be admitted to the manifold 2.

To prevent this defect I provide a cover plate 20. This plate may be rigidly secured to the piston, but preferably hingedly mounted, as at 21, said plate being also held in frictional contact with the cylinder wall 100 at all times by a leaf spring 22, as shown in Fig. 2. This cover plate fits the interior surface of the cylinder, and, as the spring 22 holds it in contact, it can readily be seen that comparatively little leakage, if any, can 105 take place through the openings 8 when the pistons assume their uppermost positions. Oil only will therefore travel through the pipe 10 and enter the tank 11 as air is entirely excluded.

An oil saver of the character here described is preferably attached to engines.

employing a splash lubricating system. It may, however, be employed where other systems are used, but has proven of great utility in the first-named instance.

- 5 The device positively stops oil from passing by the upper rings 5 into the combustion chamber. It therefore not only saves the quantity of oil that would otherwise escape, but it also prevents carbon deposits 10 from being formed in the upper portion of the cylinder and in the heads. It also prevents the spark plugs from fouling and it furthermore tends to keep the valves clean. These features are a great advantage as the 15 device not only keeps the motor cooler due to elimination of preignition, but it also saves fuel and obviously eliminates many troubles to which internal combustion engines are subjected.
- 20 The exact shape of the oil collecting grooves 7 does not form an important feature of the present invention, nor does the construction or location of the oil separating and collecting tank make any difference.

- I also wish it understood that the materials, finish and location of the several parts may be such as the experience and judgment of the manufacturer may dictate.
- 30 It has been found that the device here shown when attached to certain types of engines collects such an amount of oil that the container 11 soon becomes filled, I have, therefore, provided a float 30, which rises 35 as the oil collects. This float when reaching a certain position closes the valve 31. This valve closes the opening between the pipe 16 and the container, and therefore, immediately releases the vacuum, thus permitting 40 the check valve 14 to open, and the oil collected to drain back to the crank case. The float 30 is slidably mounted on a rod 32. A collar 33 formed on the rod serves as a stop for the float, and it also serves the function 45 of exerting a pull in a downwardly direction, which is sufficient to move the valve 31 away from its seat, thus opening the connection in the pipe 16 to permit the device to function as before described.

- 50 The action of the float 30 and the valve operated thereby is automatic, that is, overflowing of the container 11 is prevented, and the suction connection is automatically closed when the oil reaches a predetermined 55 height or level, thus permitting the container to be automatically drained from time to time.

Having thus described my invention, what I claim and desire to secure by Letters Patent is:

- 60 1. The combination with the cylinder, the piston and the crank case in an internal combustion engine, of means for removing and collecting the surplus oil delivered to the cylinder, and means connected with the

intake manifold on the engine for removing the oil collected by suction and for returning the collected oil to the crank case.

2. The combination with the cylinder, the piston and the crank case in an internal 70 combustion engine, of means for collecting the surplus oil delivered to the cylinder, means connected with the intake manifold on the engine for removing the oil collected by suction, a trap member connected with 75 said suction means adapted to collect the oil, a connection between said trap member and the crank case, and means for intermittently discharging the oil collected in the trap through said connection to the crank case. 80

3. The combination with the cylinder, the piston and the crank case in an internal combustion engine of a plurality of oil collecting grooves formed on the piston adapted to remove and collect superfluous oil delivered 85 to the cylinder and means connected with the intake manifold on the engine for removing the oil from the collecting grooves on the piston and returning it to the crank case.

4. The combination with the cylinder, the piston and the crank case in an internal combustion engine of means on the piston for removing and collecting superfluous oil delivered to the cylinder and means connected with the intake manifold on the engine for removing the collected oil and returning it to the crank case. 90

5. The combination with the cylinder, the piston and the crank case in an internal 100 combustion engine of means on the piston for removing and collecting superfluous oil delivered to the cylinder, an opening formed in the cylinder over which the piston passes during its reciprocal movement, a pipe connecting said opening with the intake manifold of the engine, a trap on said pipe line adapted to collect oil removed from the piston and means for returning the oil from 105 said trap to the crank case. 110

6. The combination with the cylinder, the piston and the crank case in an internal combustion engine of a plurality of grooves formed in the piston intermediate the upper and lower piston rings, said grooves adapted to remove and collect superfluous oil delivered to the cylinder, an opening formed in the cylinder with which the grooves of the piston alternately register during the reciprocal movement of the piston, a pipe connecting said opening with the intake manifold on the engine to remove the oil collected in the piston grooves, a tank mounted on the pipe line adapted to receive the oil removed, a pipe connecting the lower 120 end of said tank with the crank case of the engine and a check valve in the bottom of the tank adapted to close while the engine is running to permit the oil to collect in the tank and to open when the engine stops to 125 130

permit the oil collected to drain back to the crank case.

7. The combination with the cylinder, the piston and the crank case in an internal combustion engine of a plurality of grooves formed in the piston intermediate the upper and lower piston rings, said grooves adapted to remove and collect superfluous oil delivered to the cylinder, an opening formed 5 in the cylinder with which the grooves of the piston alternately register during the reciprocal movement of the piston, a pipe connecting said opening with the intake manifold on the engine to remove the oil 10 collected in the piston grooves, a tank mounted on the pipe line adapted to receive the oil removed, a pipe connecting the lower end of said tank with the crank case of the engine, a check valve in the bottom of the 15 tank adapted to close while the engine is running to permit the oil to collect in the tank and to open when the engine stops to permit the oil collected to drain back to the 20 crank case and a cover plate attached to the lower end of the piston adapted to cover the 25 opening in the cylinder when the piston passes above said opening.

8. The combination with the cylinder, the piston and the crank case in an internal combustion engine of a plurality of grooves formed in the piston intermediate the upper 30

and lower piston rings, said grooves adapted to remove and collect superfluous oil delivered to the cylinder, an opening formed in the cylinder with which the grooves of the 35 piston alternately register during the reciprocal movement of the piston, a pipe connecting said opening with the intake manifold on the engine to remove the oil collected in the piston grooves, a tank mounted 40 on the pipe line adapted to receive the oil removed, a pipe connecting the lower end of said tank with the crank case of the engine, a check valve in the bottom of the tank 45 adapted to close while the engine is running to permit the oil to collect in the tank and to open when the engine stops to permit the oil collected to drain back to the crank case, a cover plate hingedly secured to the lower end of the piston adapted to cover 50 the opening in the cylinder when the piston assumes its uppermost position and a spring engageable with the cover plate to retain it in frictional engagement with the cylinder 55 wall.

In testimony whereof I have hereunto set my hand.

DAVID S. SHEHADY.
